UNITED STATES PATENT OFFICE.

WILLIAM M. HAYNIE, OF NEWNAN, GEORGIA.

VEHICLE-JACK.

1,233,467.

Specification of Letters Patent. Patented July 17, 1917.

Application filed February 2, 1917. Serial No. 146,178.

To all whom it may concern:

Be it known that I, WILLIAM M. HAYNIE, a citizen of the United States, residing at Newnan, in the county of Coweta and State 5 of Georgia, have invented certain new and useful Improvements in Vehicle-Jacks, of which the following is a specification, reference being had therein to the accompanying drawings.

10 The invention relates to an improved vehicle jack and more particularly to a device of this nature especially adapted and useful in elevating and supporting automobiles to remove the weight from the tires when the 15 automobiles are stored and for other purposes.

An object of the invention is to provide an improved device of this nature of very simple and inexpensive construction that 20 will be strong and efficient in use.

The invention broadly comprehends a vehicle supporting frame with pairs of elevating and supporting levers connected to the frame and adapted to be swung or 25 rocked to vertically adjust the vehicle supporting frame, and a further object of the invention is to provide improved manually operable mechanism to rock the levers for raising and lowering the vehicle supporting 30 frame, and for maintaining the vehicle frame in its elevated position.

A further object of the invention is the provision of improved manually operable mechanism providing for the rocking of the 35 elevating and supporting levers to effect a gradual lifting of the frame and the easy manual operation of the device in handling heavy weights, and also providing for the quick adjustment or raising and lowering 40 of the vehicle supporting frame in dealing with the lighter weight vehicles.

The invention, with other objects and advantages thereof and the particular construction, combinations and arrangement of parts 45 comprising the same, will be understood from the hereinafter contained detail description, when considered in connection with the accompanying drawings, forming part hereof, and illustrating a preferred 50 embodiment of the invention.

In the drawings:

Figure 1 is a side elevation of a vehicle jack constructed in accordance with the 55 present invention, the vehicle elevating and supporting frame being shown in elevated position in full lines, and the lowered po-

sition of the frame and the elevating and supporting levers being indicated in dotted lines.

Fig. 2 is a top plan view of the forward 60 portion of the device.

Fig. 3 is a section taken on the line 3—3 of Fig. 1.

Fig. 4 is a section taken on the line 4—4 65 of Fig. 2.

Fig. 5 is a detail view of part of the vehicle supporting frame.

In the drawings, I have illustrated, by way of example, a particular embodiment of the invention but it will be understood that 70 variations and minor changes of the particular construction shown, as will appeal to those skilled in the art, may be made without departing from the broad principles of the invention.

The particular construction illustrated in the drawings comprises a base or supporting bed composed of two longitudinal sills or members each of which is made up of two beams 1—1 of angle iron arranged side by side with their flanges 2—2 vertically disposed adjacent each other, and their flanges 3—3 extending horizontally providing bearing surfaces. The beams 1—1 of each of the longitudinal sills or members are spaced a 75 slight distance apart by blocks 4, and the parts are rigidly fastened together by front and rear transverse tie rods 5 and nuts 6, the ends of the tie rods extending through openings in the vertical flanges 2—2 of the beam 1—1. 7 designates an additional transverse brace member of angle iron suitably secured to the longitudinal members near the front end of the base.

The vehicle supporting frame consists of 95 two longitudinal members each made up of a pair of metal beams 8—8 and having axle engaging seat members 8^a at their outer ends. 9 designates spacing blocks between the beams 8—8 of each longitudinal member, 100 and the longitudinal members are rigidly secured together by front and rear transverse tie rods 10—10 and nuts 11, the ends of the tie rods extending through suitable openings in the beams. The tie rods 10 intermediate their ends are preferably bowed or curved downwardly, and the beams 8—8 are 105 also depressed intermediate their ends, as shown, to provide clearance for the underframing and the connected mechanism of automobiles so that the members 8^a on the straight end portions of the beams 8—8 can 110

be freely engaged with the front and rear axles of the automobile.

12 designates levers for elevating and supporting the vehicle frame. The levers 12 are arranged in pairs and pivotally connected at opposite ends with the base and vehicle supporting frame respectively at opposite sides thereof, said levers being adapted to be rocked or swung to raise and lower the vehicle supporting frame. The levers, at their end portions are provided with suitable bearing eyes which are loosely engaged with the end portions of the tie rods 5 and 10 in the spaces between the longitudinal members of the base and vehicle supporting frame, the tie rods serving as pivots for the levers. Guide frames are provided for the pair of levers at the front end of the supporting frame. Each guide frame consists of a pair of curved bars 13 rigidly secured at their end portions to one of the longitudinal members of the base opposite to each other and in spaced relation to permit the levers to operate therebetween. An advantageous connection of the curved guide bars 13 with the base is obtained by offsetting the end portions of the bars 13 inwardly and securing the same together by rivets or the like to the angle beams 1 in the spaces therebetween.

The levers 12 are adapted to be rocked from the position indicated in dotted lines in Fig. 1 of the drawings to elevate and support the vehicle frame in the position indicated in full lines in Fig. 1 to lift an automobile from the ground and support the same to remove the weight of the vehicle from the tires thereof for storing purposes or in the case of overhauling or repair work, the motor vehicle being adapted to be positioned above the vehicle frame so that the straight end portions of the vehicle supporting frame will engage the axles of the vehicle and elevate and support the vehicle when the vehicle frame is raised to its elevated position.

On the guide frames are stops 14 arranged to be engaged by the forward pair of levers when they are swung to an up-right position. Stops 15 are also provided to limit the downward movement of the levers. The stops 14 and 15 are each formed by a block 16 secured between the curved bars 13 of the guide frames, said curved bars being provided with oppositely disposed outwardly offset portions forming pockets in which the stop blocks are secured by rivets or the like.

A particular important novel feature of the invention resides in the special means provided for rocking the levers 12 to raise and lower the vehicle supporting frame. The improved mechanism for this purpose comprises a shaft 17 mounted for rotation at the front of the base, said shaft extending

transversely of the base, the ends of the shafts engaging suitable bearings provided on the longitudinal members 1 of the base. On the shaft 17 are two crank arms 19 located near opposite sides of the base, the cranks being disposed parallel to each other. Pivotal link connections 20 are provided between the outer ends of the crank arms 19 and the ends of the longitudinal members of the vehicle supporting frame. The cranks and levers are so proportioned that when the elevating and supporting levers 12 occupy an up-right position the cranks extend in longitudinal alinement with the links 20, the construction providing in this particular, locking means for maintaining the vehicle supporting frame in its elevated position. Keyed to the shaft is a ratchet wheel 21, and 22 is a lever rotatably engaging the shaft at one end and held in position adjacent the ratchet wheel in any suitable manner for instance, by a collar 23. Pivotally mounted on the lever 22 is a pawl 24 adapted when the lever is oscillated in a forward direction to coöperate with the ratchet wheel 21, to rotate the shaft. 25 designates a gravity pawl for the ratchet wheel, said pawl being pivotally mounted on the forward transverse angle member 7. The ends of the shaft project a short distance from opposite sides of the base and fixedly secured thereto are operating levers 26.

It will be observed that this construction provides for a gradual lifting of the frame and the easy manual operation of the device in handling heavy weights, this being effected through the pawl and ratchet located centrally of the shaft, and also that provision is made for the quick adjustment or raising and lowering of the frame through the operating levers 26 that are fixedly secured to the ends of the shaft.

It will also be noted that the special construction of the base or supporting bed, the vehicle supporting frame and the particular location and connection of the elevating and supporting levers provide a very simple and strong construction which can be manufactured at little expense.

What I claim is:

1. A device of the class described, comprising a base, a vehicle supporting frame, pairs of elevating and supporting levers pivotally connected with the base and vehicle supporting frame at the front and rear thereof, means for limiting the movement of the levers in one direction to a vertical position, and means for rocking the levers to vertically adjust the frame, said last mentioned means including a shaft mounted for rotation upon the base near one end thereof, a crank on the shaft, a link pivotally connected at one end to the vehicle supporting frame and pivotally connected at its other

end to the said crank, and an operating lever for said shaft, said crank and link being so proportioned that when the elevating levers occupy an upright position the crank and link with their pivotal connections extend in longitudinal alinement at an upward inclination toward the vehicle frame.

2. A device of the class described, comprising a base, a vehicle supporting frame, 10 pairs of elevating and supporting levers pivotally connected with the base and vehicle supporting frame at the front and rear thereof, and means for rocking the elevating levers to vertically adjust the vehicle frame, said means including a shaft mounted for rotation upon the base at one end thereof, a crank on the shaft, a pivotal connection between the crank and one end of the vehicle supporting frame, an operating 20 lever fixedly secured to the shaft near one end thereof, and separate lever and ratchet mechanism for operating the shaft located intermediate the ends of the shaft, said lever and ratchet mechanism comprising a 25 hand lever pivotally connected at one end with the shaft, a ratchet wheel fixedly secured to the shaft, a pawl connected with said lever to coöperate with the ratchet wheel, and a second pawl pivotally mounted 30 on the base to coöperate with the ratchet wheel, said last mentioned pawl being adapted to be moved out of operative relation with the ratchet wheel, substantially as described.

3. A device of the class described, comprising a base, consisting of longitudinal members each composed of two angle beams arranged side by side and spaced a slight distance from each other, and front and 40 rear transverse tie rods rigidly securing the longitudinal members together, a vehicle supporting frame composed of parallel spaced longitudinal members each consisting of a pair of beams arranged side by 45 side and slightly spaced from each other, front and rear tie rods rigidly connecting the longitudinal members together, pairs of elevating and supporting levers pivotally connected with the base and the vehicle sup- 50 porting frame at the front and rear thereof, the ends of said levers pivotally engaging the end portions of the transverse tie rods and being positioned in the spaces between

the beams of the longitudinal members of the base and the vehicle supporting frame, 55 guides for the elevating levers, each consisting of a pair of curved plates arranged side by side and extending upwardly from the base along each side of the lever, the lower ends of the plates being secured together and to one of the longitudinal members of the base in the space between the longitudinal beams thereof and means for rocking the levers to vertically adjust the frame.

4. A device of the class described, comprising a base, consisting of longitudinal members each composed of two angle beams arranged side by side and spaced a slight distance from each other, and front and 70 rear transverse tie rods rigidly securing the longitudinal members together, a vehicle supporting frame composed of parallel spaced longitudinal members each consisting of a pair of beams arranged side by side 75 and slightly spaced from each other, front and rear tie rods rigidly connecting the longitudinal members together, pairs of elevating and supporting levers pivotally connected with the base and the vehicle sup- 80 porting frame at the front and rear thereof, the ends of said levers pivotally engaging the end portions of the transverse tie rods and being positioned in the spaces between the beams of the longitudinal members of 85 the base and the vehicle supporting frame, guides for the elevating levers, each consisting of a pair of curved plates arranged side by side and extending upwardly from the base along each side of the lever, the 90 lower ends of the plates being secured together and to one of the longitudinal members of the base in the space between the longitudinal beams thereof, blocks secured to and between the curved plate members of 95 the guide and serving as stops to limit the swinging movement of the elevating levers, and means for rocking the levers to vertically adjust the frame.

In testimony whereof I hereunto affix my 100 signature in the presence of two witnesses.

WILLIAM M. HAYNIE.
